poration of Delaware

Application November 13, 1939, Serial No. 304,087

5 Claims. (Cl. 91—55)

This invention relates to improvements in apparatus for coating flexible visible index strips.

Flexible visible index strips such as those described in United States Patent No. 1,594,112 are well known and widely used. Flexible index strips of this type are provided in continuous sheet form comprising wood veneer faced on the front and back with paper. The laminated sheet thus formed is then partially severed in the direction of its thickness or depth to permit subsequent separating into individual resilient index strips. The sheet while in partially severed condition, of course, is sufficiently coherent to be passed, for instance, around the platen of a typewriter whereby the index matter is typed upon the individual strips. Thereafter, the strips are severed completely and inserted in appropriate frames provided for that purpose.

Although use of strips constructed as above generally set forth have over long period of years been found to be highly satisfactory, yet the use of wood veneer in atmospheres of high relative humidity, and particularly in sea coast areas, has met with some difficulty due to moisture absorption and resultant warping of the individual strips.

It is therefore a prime object of this invention to provide apparatus suitable for carrying out the waterproofing flexible visible index strips while in sheet form to produce strips which are free of warping tendencies due to atmospheric moisture, by means which insure penetration and absorption of the moisture proofing materials on all sides and edges of the strip, while at the same time preserving the partially severed condition of the sheet so that the individual strips may thereafter be readily separated without destroying the protective material.

In general the invention comprises the passing of the flexible visible index strips while still in the conventional partially severed sheet form, and preferably from a roll, through a solution of a waterproofing agent, and particularly in a manner whereby the scores which extend substantially through the sheet are opened up so that penetration and absorption of the moisture-proofing material will be at a maximum including the longitudinal edges of the individual strips. The steps of operation by means of the apparatus further comprise the drying of the treated sheet which preferably includes a dry heating means, such as a radiant heat source, and frequently re-opening the scores to permit the longitudinal edges of the strips an opportunity to dry and to substantially preserve the sheet in its original

partially scored and readily severable condition.

Other objects and advantages of my invention will be apparent from the following specification and accompanying drawings, wherein:

Fig. 1 is a face view of a frame showing individual flexible visible index strips mounted in position.

Fig. 2 is a perspective view of an individual strip after being separated from a sheet.

Fig. 3 is a longitudinal sectional view of a partially severed sheet of index strips.

Fig. 4 is a perspective view of an apparatus for carrying out the moisture-proofing treatment of the strips while in sheet form.

Fig. 5 is an enlarged detail sectional view of the impregnating portion of the apparatus.

Referring to the drawings, a sheet of index strips 10 as generally constructed comprises a thin ply of wood veneer 11, such as red gummed veneer which is extremely porous, faced with a sheet of paper 12 capable of receiving typewriting or other imprint, and backed preferably with a thin sheet of material 13 such as onion skin paper, the whole being cut transversely to define strips 14. In cutting the sheet, the cut is made through the facing sheet 12 and through, or substantially through, the wood veneer 11, leaving the backing sheet 13 intact. This sheet may be wound around the platen of a typewriter or other imprinting device, and identifying data put upon the separate strips. Upon removal from the imprinting device the strips may be severed from the sheet singly or in numbers, and inserted in a suitable frame, generally indicated as 15, by doubling the flexible strips and inserting them beneath the side flanges 16 of the frame.

As hereinbefore stated, the formation of the sheets, their use, the separation of the strips and their insertion in frame holders as above outlined have over a long period of years been found generally satisfactory. However, in humid or moist atmospheres, and especially in sea coast areas it has been found that due to the extreme porosity of the wood veneer component of the strips, if unprotected, moisture is absorbed from the atmosphere. This in time warps and otherwise deteriorates the strips and causes them to become loose and even to fall out of the mounting frame. I have found, however, that by taking advantage of the porosity of the strips a waterproofing agent may readily be incorporated to render the strips moisture resistant and thereby overcome difficulties due to warping or deterioration on long usage.

Water-proofing of absorbent materials and

water-proofing agents are generally known, but I have found that for the purpose of rendering flexible visible index strips moisture-resistant a nitro cellulose solution commonly known as clear lacquer is highly satisfactory. It is generally preferred to carry out the waterproofing operation after the strips have been imprinted so that the imprinted surface may be better protected and also for the reason that a greater amount of protective agent may be incorporated. However, the sheets may be treated before being imprinted, but in such usage the amount of protective material that can be incorporated must be limited consistent with the ability of the facing sheet to thereafter receive an imprint or the particular process of imprinting. On the other hand, as will be understood by those skilled in the art, the amount of solvent in the lacquer solution must be limited in treating a printed surface whereas with blank surfaces the amount of solvent is not a consideration. For waterproofing the sheets after they are imprinted it is therefore preferable when utilizing the nitro cellulose clear lacquer solution to have a viscosity of approximately eight minutes through a Ford #4 cup, and when treating the imprinted sheets a much thinner solution may be used.

It is also most desirable that the water-proofing treatment be carried out on the sheets as a unit as distinguished from the individual strips. The reasons for this as far as pre-treating the sheets prior to imprinting is self evident from the nature of the material and its inherent use. Treatment of the imprinted strips in sheet form is also necessary in order that the impregnating may be uniform, that the operation may be carried out rapidly and economically, and that the strips be maintained in an orderly manner and in their original arrangement, so that their insertion either singly or in groups into the holder frame may be facilitated.

In order to fully protect the strips and carry out their impregnation while in sheet form it is necessary that steps be taken to insure that the lacquer be applied to the longitudinal edges of the strips, and it is further essential that in the course of such treatment that the drying of the lacquer will not seal the lines of partial severance so that ease in separation of the strips will not be impaired and the protective material will not be pulled away. Such method and objects may be readily accomplished by means of the apparatus shown in Figs. 4 and 5.

The apparatus comprises a base 20 having a mounting support 21 extending vertically therefrom, the mounting support being adapted to carry a plurality of rolls and reels in spaced apart relationship, hereinafter described. Extending from an intermediate point of the surface of the mounting support is a spindle 22 for carrying a feed reel 23, and one or more auxiliary spindles 24 for carrying additional rolls of material to be treated as will be hereinafter set forth. On the base 20 adjacent one end thereof is mounted an impregnating tank 25, within which is contained a roll 26 of relatively small diameter with reference to the width of the strips to be treated, and a pair of pinch rolls 27, preferably covered with rubber or the like material. The roll 26 and the pinch rolls 27 are suitably journaled in the spring bearing blocks 28, the whole assembly being removable from the tank 25 for ease in cleaning. It will be noted that the block 28 is formed with an oblique slot 29 extending to adjacent one corner thereof and is

provided with ears 30 and an adjusting screw 31 extending through one of the ears and being threaded into the other. By manipulation of the screw 31 the peripheral relationship or compression of the pinch rolls 27 may be varied or adjusted. While I have shown a preferred manner of mounting and adjusting the pinch rolls 27, it will be understood that other conventional squeeze, draw or wringer rolls and adjustable mounting means therefor may be utilized within the scope of my invention.

Mounted on the support 21 are the spaced apart flanged rolls 32, 33 and 34 carried on suitable spindles extending from or journaled in the support, the rolls 32 and 33 being vertically spaced from the base 20 and mounted adjacent the opposed upper corners of support 21, and roll 34 being adjacent to the base 20 at the end opposed to the tank 25. Although not shown, additional like rolls may be interposed. An additional spindle 35 extends from the support 21 spaced from the base 20 and adjacent to a vertical plane extending through the axes of the rolls 33 and 34, and mounted on the spindle 35 is a wind-up reel 36.

Operation of the apparatus may be accomplished by means of a motor and speed reducer mounted on the base 20, or by means of a crank and suitable gearing (none of which is shown), the motive power being preferably applied to the pinch rolls 27, and from which motive source there may additionally extend a belt such as a spring belt to wind up reel 36, to furnish a positive wind-up means. A drying means adapted to quickly dry the lacquered material is interposed in the path of travel thereof, as indicated at 37 preferably in the path of horizontal travel between the rolls 32 and 33. It will be understood, however, that the heat source means 37 as illustrated is diagrammatic and may comprise a drying oven or the like, although it is preferred to utilize an infra-red lamp or as indicated by the dotted lines a pair of opposed lamps to furnish radiant heat which will give a dry heat as opposed to hot air or convection heating means which entails moisture condensation which I desire to avoid.

In carrying out the moisture proofing process the tank 25 is kept supplied with lacquer to a level well above the roll 26. A reel 23 of strip material in sheet form 10, as supplied in roll form or as rewound after being printed, is mounted on spindle 22 and drawn through the lacquer solution in tank 25, around roll 26 and then upwardly between pinch rolls 27, the sheet being introduced so that the unsevered backing sheet 13 lies against the surface of the roll 26, and likewise continues to lie in the same relationship in its subsequent passage around rolls 32, 33, 34 and onto wind-up reel 36, so as to prevent rupture.

It will be noted that the sheet 10 is introduced at an oblique angle and the roll 26 is positioned with respect to rolls 27 so that the sheet is fed between the rolls 27 in a plane substantially perpendicular to a plane passing through their axes, and thus the plane at which the sheet material is introduced is at an oblique angle to the plane of the sheet as it passes around and leaves the roll 26. This action causes the sheet, the strips of which are relatively wide with respect to the diameter of roll 26 to become acutely bent around the roll 26 exposing the longitudinal edges of the strips and particularly the edges of the porous wood veneer component to the lacquer impregnant insuring complete protection.

As the impregnated sheet passes between the pinch rolls 21, which may be adjusted as previously set forth to control the thinness or thickness of the coating, the applied pressure additionally acts to more or less force the lacquer through any small holes or crevices that may have escaped coating when passing freely through the bath, and aids in insuring thorough covering and impregnation.

The impregnated sheet is then drawn upwardly, and since atmospheric drying immediately sets in, it is caused to pass at substantially a right angle around roll 32. This change of direction causes an angular separation of the strips to permit the longitudinal edges to dry and to prevent their adhesion or the formation of a unitary film over the severed facing sheet. The sheet is then caused to pass horizontally over roll 33 whereat its direction of travel is likewise changed in the same manner and for like reasons as at roll 32. For speed in operation and completion of the process drying means is interposed in the path of the sheets travel, and for the additional reason that in the use of lacquer with an imprinted sheet rapidity of drying is desirable. I have found that a suitable point for carrying out the heat drying treatment is on the horizontal run of the sheet, and somewhat adjacent to roll 32. While I have diagrammatically indicated a heating means 37, I prefer to use a source of radiant heat which will give dry heat without undue moisture condensation, and for this purpose I prefer to use a pair of infra-red lamps one on each side of the traveling sheet in suitable reflectors, as indicated at 37 opening onto the opposed faces of the sheet. After the sheet is carried over roll 33 it is caused to pass over roll 34 and thereafter wound up onto reel 36. It will be noted that reel 36 is carried on a spindle inwardly of the major run of the sheet and adjacent to roll 33, which causes the sheet to be carried over roll 34 at an acute angle and thereby assuring good angular separation of the strips, drying of the longitudinal edges of the strips, and consequent ease in their later separation and elimination of tendency toward separation of the protective coating from the face of the strips.

As hereinbefore set forth the partially severed sheet of strip material comprises a backing of thin tissue such as onion skin paper which remains unsevered during imprinting and during the impregnating and protective treatment herein described. However, due to the fact that a thin backing paper of this nature is utilized, in the carrying out of the within process the thin sheet becomes so permeated with the treating solution that when the strips are later completely severed, either manually or by suitable mechanical means, the severed or separated edges of this backing sheet are also found to be protected due to the penetration and permeation of the protective impregnant.

In carrying out the operation it will be evident that if the initially treated sheet, or as much of a roll as is required to make a complete run from the feed reel to the wind-up reel, is desired to be kept under the slight tension necessary to insure angular separation of the strips in their passage around the several rolls, a dummy sheet may be threaded through the apparatus and spliced to the first roll, and the same procedure may be carried out with respect to the end of the roll. For continuity of operation there is provided the auxiliary spindle 24 on which may be placed a second reel of rolled up sheet ma-

terial 23', and as reel 23 becomes exhausted the material on reel 23' may be spliced thereto, and the procedure alternated for added continuity of operation.

It may also be noted that when rolls of sheet strip material are typed on an automatic machine such as a tabulating machine, they are rewound automatically and taken off, and this of course puts the indexes in reverse order in that an operation of rewinding the roll is necessary to bring the indexes back to their proper alphabetical or original arrangement. The herein in coating may thus be accomplished conveniently during this necessary rewinding operation.

I claim as my invention:

1. Apparatus for moisture proofing flexible visible index strips in continuous sheet form composed of a porous wood veneer body portion faced and backed with paper and scored through the facing paper and wood body portion comprising a receptacle containing a body of moisture proofing solution, a roll submerged in the solution about which a continuous sheet of said strip material is trained with its unsevered backing paper in contact therewith for immersion in the solution, the said roll being of relatively small diameter with respect to the width of said strips, and means comprising a pair of pressure rolls constructed and arranged with respect to said submerged roll for vertically withdrawing said sheet from said solution in planar formation at an acute angle to the plane of its introduction to cause said sheet to be acutely bent around said roll and to expose the longitudinal edges of said strips to said solution while passing therethrough.

2. Apparatus for moisture proofing flexible visible index strips in continuous sheet form composed of a porous wood veneer body portion faced and backed with paper and scored through the facing paper and wood body portion comprising a receptacle containing a body of moisture proofing solution, a roll submerged in the solution about which a continuous sheet of said strip material is trained in contact with its unsevered back for immersion in the solution, the said roll being of relatively small diameter with respect to the width of said strips, means for withdrawing said sheet from said solution at an acute angle to the plane of its introduction to cause said sheet to be acutely bent around said roll and to expose the longitudinal edges of said strips to said solution while passing therethrough, and a plurality of exteriorly mounted rolls about which the sheet is trained in contact with its unsevered back for drying thereof, the said exterior rolls being spaced apart and positioned whereby the sheet is caused to intermittently flex in a direction toward said unsevered back only and expose the longitudinal edges of the strips for separated drying.

3. Apparatus for moisture proofing flexible visible index strips in continuous sheet form composed of a porous wood veneer body portion faced and backed with paper and scored through the facing paper and wood body portion comprising a receptacle containing a body of moisture proofing solution, a roll submerged in the solution about which a continuous sheet of said strip material is trained in contact with its unsevered back for immersion in the solution, the said roll being of relatively small diameter with respect to the width of said strips, means for withdrawing said sheet from said solution at

an acute angle to the plane of its introduction to cause said sheet to be acutely bent around said roll and to expose the longitudinal edges of said strips to said solution while passing therethrough, a plurality of exteriorly mounted rolls about which the sheet is trained in contact with its unsevered back for drying thereof, the said exterior rolls being spaced apart and positioned whereby the sheet is caused to intermittently flex in a direction toward said unsevered back only and expose the longitudinal edges of the strips for separated drying, and radiant heat drying means interposed in the path of travel of the sheet around said exterior rolls.

4. Apparatus for adding a moisture proofing saturant and coating to flexible visible index strips in sheet form composed of a porous wood veneer body portion faced and backed with paper and scored through the facing paper and wood body portion which comprises a receptacle containing a body of moisture proofing solution, a roll submerged in said solution about which a continuous sheet of said strip material is trained for immersion in the solution, means for introducing said sheet at an oblique angle, and a pair of pressure rolls for withdrawing the sheet substantially vertically from the solution and to remove excess saturant therefrom, the said immersion roll being of relatively small diameter with respect to the width of said strips to cause said sheet to be bent acutely around it and to expose the longitudinal edges of the strips to said solution, a wind-up reel and a plurality of intermediate exteriorly mounted rolls for supporting the sheet for drying travel thereof, the said exterior rolls being spaced apart and positioned whereby the sheet in its said passage is caused to intermittently flex in a direction toward said unsevered back only and ex-

pose the longitudinal edges of said strips to individualized drying, and heat drying means comprising infra-red lamps interposed in the said path of sheet travel.

5. Apparatus of the class described comprising a receptacle containing a body of saturant solution, a roll for carrying a continuous sheet of strip material composed of a porous wood veneer body portion faced and backed with paper and scored through the facing paper and wood body portion therethrough and for immersing it in said solution of relatively small diameter with respect to the width of the strips, a pair of adjustably mounted horizontally aligned draw rolls, a vertically extending frame comprising means for mounting a feed reel and wind-up reel for said sheet material intermediate thereof, a plurality of sheet supporting rolls mounted on said frame outwardly of said reels in spaced apart relationship, the said feed reel being positioned to cause said sheet to pass into said receptacle at an oblique angle and the said immersion roll being positioned adjacent to said draw rolls whereby the sheet is fed between them in a plane substantially perpendicular to a plane passing through their axes and caused to be bent acutely around said immersion roll in contact with its unsevered back to flex said sheet and expose the longitudinal edges of said strips to said solution, the said sheet supporting rolls being adapted to cause said sheet in its passage from said draw rolls to said wind-up reel to be exposed to drying conditions and to flex said sheet while passing thereover in a direction toward said unsevered back only to expose the longitudinal edges of the strips thereof, and radiant heat drying means directed against a plane of travel of the sheet.

CHARLES E. ATTWOOD.
